UNITED STATES PATENT OFFICE.

CHARLES D. LANNING, OF DORCHESTER, MASSACHUSETTS.

STOP-MOTION FOR LOOMS.

1,147,249.

Specification of Letters Patent. Patented July 20, 1915.

Application filed March 12, 1907. Serial No. 362,015.

To all whom it may concern:

Be it known that I, CHARLES D. LANNING, a citizen of the United States, residing at Dorchester, in the county of Suffolk and 5 State of Massachusetts, have invented an Improvement in Stop-Motions for Looms, of which the following description, in connection with the accompanying drawings, is a specification, like letters on the drawings 10 representing like parts.

This invention relates to stop motions which, while they may be of general application, are primarily intended for application to a loom to stop the same upon the 15 occurrence of a warp fault, and preferably through mechanical agencies.

It is customary to employ detectors or drops individually supported upon the warp threads of a loom, so that upon the break- 20 age of a thread or undue slackness thereof the detector or drop pertaining to that thread assumes an abnormal position and is impinged upon by a feeler, resulting in stop- page of the loom. Such detectors, as gen- 25 erally constructed are composed of a thin strip of metal, and since they have heretofore borne the full or substantially the full strain of the feeler consequent upon the release thereby of the stopping mechanism 30 for the loom, they quickly become bent or otherwise injured.

So far as I am aware, I am the first to relieve the detectors of the strain of the feeler, transferring the same to an abut- 35 ment, so that the strain consequent upon the stopping of the loom is not only not borne by the detectors but tends to be positively relieved by the action of the stopping mechanism.

40 Other features of my invention will be more readily apparent upon a detailed description thereof.

While my invention may be embodied in a great variety of mechanisms widely dif- 45 fering in structure and operation, I have, in order that the principles of the invention may be made clear, set forth one embodiment thereof in the accompanying drawings, wherein—

50 Figure 1 is a side elevation of a portion of the loom frame showing my invention applied thereto, the feeler being represented as having just impinged upon an abnor- mally positioned detector. Fig. 2 is a side 55 elevation of a portion of the mechanism disclosed in Fig. 1 upon a larger scale and

representing the same position of parts; Fig. 3 is a side elevation of the same parts but representing the detectors as normally positioned, and hence the feeler as partaking of its normal movement; and Fig. 4 is a side elevation representing the movement of the various parts consequent upon the abnormal position of the detector, whereby 60 the loom is stopped.

65 Referring specifically to that single type or embodiment of my invention herein selected for illustration, the frame of the loom is indicated at 1, it being of any suitable type.

70 If desired, my invention may be applied to the character of loom disclosed in the patent to Coldwell and Gildard, No. 690,636, though it will be understood that I am in no wise to be limited to any particular type 75 or character of loom. The leasing members of the loom are represented at 2—2 and are supported in the loom frame in any desired manner to sustain in the usual manner the warp threads 3. Preferably between the 80 leasing members, detectors herein shown as drops 4 are mounted individually upon the warp threads. While I am not to be limited to the type of drop herein shown excepting when specifically so stated, preferably I 85 employ an open drop as clearly represented, as I have found in practice that it is preferable to position the drops after the warp drawing operation and after the threads are in the loom than to draw the warps 90 through the drops. Furthermore an open drop is more flexible and limber at its lower end, and in the event of the employment of an electrical stop motion a better contact is 95 made.

95 As clearly represented, the drop is mounted upon or straddles one of a pair of bars or guides 5. Herein such bars or guides are positioned so low as to be but slightly above the path of movement of the feeler. 100 By so positioning them a support is afforded for the drop at the point where it is most effective. Upon the occurrence of a warp fault, consisting either of warp breakage or undue slack, a drop of whatever character employed assumes an abnormal position or a lower position as specifically indicated in Fig. 2, thereby bringing it into the path of movement of a feeler 6. Here- 105 tofore, feelers have been employed adapted to be reciprocated or vibrated in a deter- 110 mined path, into which path the abnormally

positioned drop moves, thereby checking or interrupting the movement of the feeler and through intermediate mechanism stopping the loom. So far as I am aware, in prior 5 constructions the strain of stopping the loom has been borne by the drop although attempts have been made to prevent deformation of the drop by lateral or other guides therefor.

10 One of the important objects of my invention is to remove from the abnormally positioned drop the strain of stopping the loom by transferring it from the drop to some suitable abutment. It is apparent that 15 this may be accomplished by mechanisms widely varying in construction and operation but involving this fundamental idea. In practice, I have found the construction herein set forth to be efficient. If desired, a 20 single feeler 6 may be employed to coöperate with two banks of drops as represented. While the feeler may be mounted to move in any suitable manner toward and from the drops, herein I have loosely mounted 25 the same upon a rock shaft 7 suitably supported in the loom frame, providing such feeler with the downwardly extending portion 8 and lateral wings 9—9. In order to rock the shaft 7, whereon, in this type of 30 the invention, the feeler 6 is mounted, I may employ any suitable means herein shown as an actuator. Herein for the purpose I employ an actuator 10 fast upon the rock shaft 7 and having a forked lower 35 end 11 to receive between the members thereof of a cam or eccentric 12 mounted upon shaft 13. In the present type of the invention, I employ the weft cam or a cam upon the shaft that operates the weft hammer. In 40asmuch as this shaft usually rotates at half the speed of the main driving shaft, the rate of movement of the feeler and hence its momentum when it encounters an abnormally positioned drop or detector are much lessened, thus reducing liability of damage to 45 such detector. While the actuator and feeler may be operatively connected in any suitable manner, preferably I connect the same for relatively yielding and herein effect this 50 by pivoting upon the actuator a pair of downwardly extending lever members 14, which herein have a flat broadened face to receive between them a laterally extending head 15 formed upon the lower end of the 55 member 8 of the feeler. As clearly apparent, the said head 15 projects beyond the plane of the member 8 to permit proper engagement therewith of the said faces upon the lever members 14. The face of the 60 actuator 10 between the adjacent edges of the lever members 14 is provided with a stop 15', which when said lever members 14 are normally positioned, as in Fig. 1, engage both of said inner edges. Preferably a coiled or other spring 16 is employed

to connect the lever members 14, thus normally maintaining them in parallel position but permitting movement of either one of said levers with respect to the other and with respect to the actuator upon engagement 70 of the feeler 6 with an indicating drop bar, as will be evident from a comparison of Figs. 1, 2 and 3 with Fig. 4. By reason of the reduced rate of speed of the feeler, the spring 16 may be of a delicate character. 75 Whether the head of the feeler 6 be displaced to the right or to the left upon contact of an indicating drop bar, one of the lever members 14 will be held from movement relative to the actuator by reason of 80 its engagement with the stop 15', and the other lever member 14 will be moved away from said stop, and thus expand the spring 16 as indicated in Fig. 4. The spring 16 thus tends to restore the parts to their position with respect to the actuator that is shown in Figs. 1, 2 and 3.

As stated, if I employ a connection between the feeler and the actuator, it may be of any suitable type. In the present type 90 of my invention, I employ an abutment or abutments operatively connected to and herein rigid with the feeler, which abutments are therefore, in this form of my invention, movable and in the normal operation of the loom are confined to a certain inoperative position or to a path of movement that may be termed an inoperative path. Upon impingement of the feeler upon an abnormally positioned drop, however, an 100 abutment of any suitable nature is rendered operative by any suitable connection and in the present instance, wherein the abutment is movable, by holding or positioning it in an operative position, so that it may be impinged upon by a member of any suitable character to effect the stoppage of the loom, while at the same time the abutment receives the full strain consequent upon such 105 stopping movement.

While the abutment or abutments may be constructed in many different ways whether or not rigid with or carried by the feeler, herein I mount upon or form with the feeler 6 the lateral wings 9, which during the normal working of the loom traverse a determined inoperative path as indicated in Fig. 3. Herein the abutments 9 extend laterally from the rock shaft 7, so that the strain received by either abutment is transferred immediately to the rock shaft 7.

Any suitable mechanism may be employed to be actuated and herein by the abnormal or operative positioning of an abutment to effect stoppage of the loom. Herein, I employ a movable member, though I am not to be restricted thereto save as expressly stated. While such movable member may be mounted and operated in any suitable manner, in the present type of the invention I employ a 125 130

feeler actuated member 17, pivotally mounted at 18 upon the actuator 10 and operatively connected as by means of a rod 19 with a knock-off lever 20 (see Figs. 1 and 4) 5 pivotally mounted at 21 upon the loom frame and having two shouldered portions 22 and 23 at opposite sides of the pivot 21. My invention may be embodied in a feeler actuated member of any desired type or embodiment. 10 Such member, however constructed, I herein also term a secondary feeler or bunter, inasmuch as it has this function with reference to an abutment of whatever type employed, it feeling to ascertain whether an abutment is operatively positioned. 15 If such member in its feeling action finds an operatively positioned abutment, stoppage of the loom results. In the normal working of the loom, each of said 20 shoulders is adapted, as indicated in Fig. 1, to engage the shipper lever 24, which may be retained in the usual notch to be released to stop the loom. Viewing Figs. 1 and 4, it will be apparent that movement of the 25 knock-off lever 20 in either direction will serve to stop the loom.

Herein the upper end of the feeler actuated member 17 is forked, each member 24 and 25 of such forked portion having an in-turned portion 26 and 27 adapted, in the normal working of the parts, to partake of a movement in a fixed path and to a fixed extent. In accordance with this type of my invention, I vary the path of movement of 30 the feeler actuated member 17 in order to effect the stoppage of the loom, and herein this is specifically accomplished by interposing in the normal path thereof an abutment 9 to terminate or shorten the stroke of said 35 member interposed in its path. I may, however, employ any suitable actuator and vary the path of movement thereof in other ways as, for example, by normally imparting thereto a minimum length of stroke, which, 40 upon the occurrence of a warp fault, is lengthened to effect in any suitable manner the actuation of the stopping mechanism.

Viewing Fig. 3, it will be apparent that 45 in the normal operation of the parts the path of movement of each abutment 9 is such that the path of movement of the feeler actuated member, bunter, or secondary feeler 17 is not altered or affected thereby. When, however, the feeler 6 in its feeling movement meets an abnormally positioned drop as indicated in Fig. 2, its movement is interrupted, and the abutment 9 is lifted above or displaced from its normal path of movement, as indicated in Fig. 2, bringing it into 50 the path of movement of one of the in-turned ends 26 of the feeler actuated member or bunter 17. In Fig. 2, the feeler 6 is represented as having just engaged the abnormally positioned drop, thereby abnormally 55 positioning an abutment 9, because of the

continued movement of the actuator 10, which further movement is not partaken of by the feeler 6. Upon the continued movement of the cam 12 the actuator 10 is moved from the position indicated in Fig. 2 toward 70 that indicated in Fig. 4, thereby impinging the inturned end 26 upon the corresponding abutment 9. During the normal operation of the parts, the feeler actuated member 17 has moved bodily with the actuator 10 and 75 has rocked about the point of connection X of the rod 19 and such feeler actuated member as a center. When, however, the portion 26 engages the corresponding abutment 9, as indicated in Fig. 4, the further movement of 80 the upper end of the feeler actuated member 17 is interrupted. Since, however, the movement of the actuator 10 toward the right, viewing Fig. 4, continues, the point of rocking movement of the feeler actuated 85 member 17 is transferred from its lower end to the portion 26 at its upper end, and accordingly bodily movement of the lower end ensues, and hence a movement of the rod 19 to the right viewing Fig. 4 or in the direction of the arrow therein. The knock-off lever 20 is likewise moved to the right and the shoulder 23 releases the shipper lever 24 from its notch to stop the loom. It is apparent that if an abnormally positioned 90 drop were engaged by the feeler 6 in its opposite stroke, the inturned portion 27 of the feeler actuated member 17 would in the same manner engage its abutment 9 to effect a movement of the rod 19 to the left 95 viewing Fig. 4, whereby the loom would be stopped through engagement of the shoulder 22 of the knock-off lever with the shipper lever 24.

I may form the abutments 9—9 and the 100 in-turned portions 26 and 27 in any suitable manner to facilitate proper engagement of the parts. Herein I have represented each abutment 9 as concaved, and the parts 26 and 27 as convexed. If desired, this construction may be reversed or varied.

While in the manner indicated the strain 105 of stopping the loom is borne by an abutment and the rock shaft from which the abutment extends, preferably I so construct or proportion the parts that in the impingement of the feeler actuated member upon an abutment, the feeling portion of the feeler is removed from engagement with the abnormally positioned drop. This result may 110 also be accomplished in any desired manner in other types of my invention. In Fig. 4, I have indicated such operation of the parts in the present type of the invention. While this result may be accomplished in any desired manner, herein I effect the same by making the radius of the path of movement of the in-turned portions 26 and 27 of the feeler actuated member 17 about the point 115 of connection X of such member with the 120

125 130

rod 19 longer than the distance between such point of connection X with the rod 19, and the axis of the rock shaft 7. Thereby, either inturned portion 26 or 27 engages an abutment 9 with such a direction of movement as to force the abutment upwardly and hence to move the feeling portion of the feeler rearwardly or from the abnormally positioned drop. It is apparent that were the path of movement of the portion 26 or 27 such as to tend to move an abutment 9 downwardly, the feeling portion of the feeler would be retained in engagement with the abnormally positioned drop. In other types 15 of my invention I may accomplish this result in other ways as will be readily apparent to those skilled in the art.

I desire it to be understood that my invention may be embodied in mechanisms 20 differing widely from that illustrated which is selected merely as an effective means for accomplishing the results that are to be secured.

Having thus described one type or embodiment of my invention, I desire it to be understood that although I have employed specific terms, they are used in a descriptive and generic sense and not for purposes of limitation, the scope of the invention being set forth in the following claims.

I claim—

1. A stop mechanism comprising thread supporting detectors adapted to be abnormally positioned upon thread fault, a feeler 35 to engage an abnormally positioned detector, an actuator for said feeler, means driven at a less speed than the main drive shaft of the machine for operating said actuator, means operatively related to the feeler to 40 remove from the abnormally positioned detector engaged by the feeler the strain of loom stoppage, so that the strain of loom stoppage is not borne nor shared by the abnormally positioned detector, and stopping 45 mechanism made effective by the said last mentioned means.

2. A stop mechanism comprising thread supported detectors adapted to be abnormally positioned upon thread fault, a feeler 50 to engage an abnormally positioned detector, a shaft whereon the same is mounted, said shaft being adapted to receive the strain of loom stoppage, an actuator for the feeler operatively related thereto, a rotatable member 55 operatively related to and adapted to move said actuator, an abutment positioned in impact position upon engagement of the feeler with an abnormally positioned detector and coöperating with said shaft to 60 transfer the strain of loom stoppage thereto, a member or bunter adapted to engage said abutment when in impact receiving position, and stopping mechanism operatively connected with said member.

3. A stop mechanism comprising thread

supported detectors adapted to be normally positioned upon thread fault, a feeler adapted to move in a path that is intercepted by an abnormally positioned detector, an actuator for said feeler, means driven at a less speed than the main drive shaft of the machine for operating said actuator, stopping mechanism, and means to remove the strain of loom stoppage from an abnormally positioned detector intercepting the feeler, and 75 operatively connected to said stopping mechanism so that the strain of loom stoppage is not borne nor shared by the abnormally positioned detector.

4. A stop mechanism comprising warp supported detectors adapted to be abnormally positioned upon warp fault, a feeler adapted to move in a path that is intercepted by an abnormally positioned detector and operative upon either stroke, an actuator for said feeler, stopping mechanism, and means operative upon either stroke of the feeler in the event of abnormal position of the detector to remove the strain of loom stoppage from such detector.

5. A stop mechanism comprising warp supported detectors adapted to be abnormally positioned upon warp fault, a feeler adapted to move in a path at an angle to the series of detectors and that is intercepted 95 by engagement with an abnormally positioned detector, an actuator for said feeler, an abutment movable with the feeler and adapted upon engagement of the feeler with an abnormally positioned detector to be held 100 in impact position, a member or bunter adapted to coöperate with said abutment when in impact position, stopping mechanism and operative connections between said member and the stopping mechanism.

6. A stop mechanism comprising warp supported detectors adapted to be abnormally positioned upon warp fault, a feeler adapted to move in a path that is intercepted by an abnormally positioned detector, an actuator for said feeler, an abutment extending from the feeler transversely to the series of detectors and adapted upon engagement of the feeler with an abnormally positioned detector to be held in impact position, a member adapted 110 to engage said abutment when in impact position, stopping mechanism and operative connections between said member and the stopping mechanism.

7. A stop mechanism comprising warp supported detectors adapted to be abnormally positioned upon warp fault, a feeler adapted to move in a path that is intercepted by an abnormally positioned detector, an actuator for said feeler, means driven at a less speed than the main drive shaft of the machine for operating said actuator, stopping mechanism, and means to remove, prior to loom stoppage, the strain of the feeler from an abnormally positioned detector intercept- 125

ing the feeler, whereby the strain of loom stoppage is not borne nor shared by the abnormally positioned detector.

8. A stop mechanism comprising warp supported detectors adapted to be abnormally positioned upon warp fault, an oscillatory feeler adapted to move in a path that is intercepted by an abnormally positioned detector, an actuator for said feeler, means distinct from the lay for operating said actuator, an abutment adapted upon engagement of the feeler with an abnormally positioned detector to be held in impact position, a member relatively movable with respect to said abutment and adapted to coöperate with said abutment when the latter is in impact position, stopping mechanism, and operative connections between said member and said stopping mechanism.
9. A stop mechanism comprising thread supported detectors adapted to be abnormally positioned upon thread fault, a feeler adapted to move in a path that is intercepted by an abnormally positioned detector, an actuator for said feeler having a to and fro path of movement, a feeler actuated member carried by the actuator and having movement relative to the feeler, said feeler actuated member being normally movable in a determined path and adapted to have its path of movement modified upon engagement of the feeler with an abnormally positioned detector, an abutment positioned by the feeler for engagement with the feeler actuated member stopping mechanism and a stoppage actuating connection between the feeler actuated member and the stopping mechanism rendered operative when such path of movement is affected.
10. A stop mechanism comprising thread supported detectors adapted to be abnormally positioned upon thread fault, a feeler adapted to move in a path outside said detectors and that is intercepted by engagement with an abnormally positioned detector, an actuator for said feeler, an abutment, the abutment and feeler having a common support, stopping mechanism, and means to transfer the strain of machine stoppage from the abnormally positioned detector to said abutment.
11. A stop mechanism comprising thread supported detectors adapted to be abnormally positioned upon thread fault, a feeler adapted to move in a path that is intercepted by an abnormally positioned detector, an actuator for said feeler, means distinct from the lay for operating said actuator, an abutment rigid with the feeler, and extending therefrom at an angle to the plane of the series of detectors, a moving member distinct from the lay and provisions whereby said abutment is held in the path of the moving member upon the occurrence of a thread fault.

12. A stop mechanism comprising thread supported detectors adapted to be abnormally positioned upon thread fault, a feeler adapted to move in a path that is intercepted by an abnormally positioned detector, an actuator for said feeler, a plurality of abutments carried by the feeler and normally in inoperative position, means whereby upon the occurrence of a thread fault one of said abutments is operatively positioned, and stopping mechanism rendered operative thereby.

13. A stop mechanism comprising warp supported detectors adapted to be abnormally positioned upon warp fault, a feeler adapted to move in a path that is intercepted by an abnormally positioned detector, an actuator for said feeler, stopping mechanism, an abutment rigid with the feeler and normally inoperative, and means operative upon either stroke of the feeler and including a bunter movable with the actuator whereby the loom is stopped upon the occurrence of a warp fault.

14. A stop mechanism comprising warp supported detectors adapted to be abnormally positioned upon warp fault, a feeler adapted to move in a path that is intercepted by an abnormally positioned detector, an actuator for said feeler, said actuator having an unvarying movement, operating means therefor driven at a less speed than the main drive shaft of the machine, a bunter operated independently of the lay and operatively related to the feeler to remove from the abnormally positioned detector intercepting the feeler the strain of loom stoppage, whereby the strain of loom stoppage is not borne nor shared by the abnormally positioned detector, and stopping mechanism made effective by the bunter.

15. A stop mechanism comprising thread supported detectors adapted to be abnormally positioned upon thread fault, a feeler adapted to move in a path that is intercepted by an abnormally positioned detector, an actuator for said feeler, a support for the actuator and feeler, stopping mechanism, and means operative upon the occurrence of a thread fault to transfer the strain of loom stoppage from the feeler to said support.

16. A stop mechanism comprising warp supported detectors adapted to be abnormally positioned upon warp fault, a feeler adapted to move in a path that is intercepted by an abnormally positioned detector, an actuator for said feeler, a shaft whereon the actuator is mounted, stopping mechanism, and means operative upon the occurrence of a warp fault to transfer the strain of loom stoppage directly from the feeler to said shaft.

17. A stop mechanism comprising warp supported detectors adapted to be abnormally positioned upon warp fault, a feeler

- adapted to move in a path that is intercepted by an abnormally positioned detector, an actuator for said feeler, a shaft whereon the feeler is mounted, a member movable relative to the actuator, stopping mechanism, and means operative upon the occurrence of a warp fault and co-acting with said member to transfer the strain of loom stoppage to said shaft.
18. A stop mechanism comprising warp supported detectors adapted to be abnormally positioned upon warp fault, a feeler adapted to move in a path that is intercepted by an abnormally positioned detector, an actuator for said feeler, a shaft whereon the feeler and actuator are mounted, stopping mechanism, and means operative upon the occurrence of a warp fault to transfer the strain of loom stoppage to said shaft.
19. A stop mechanism comprising warp supported detectors adapted to be abnormally positioned upon warp fault, a feeler adapted to move in a path that is intercepted by an abnormally positioned detector, an actuator for said feeler, said actuator having a rock shaft, an abutment on said rock shaft operatively associated with said feeler, stopping mechanism operatively associated with said rock shaft, and means operative upon either stroke of the feeler whereby upon the occurrence of a warp fault the strain of loom stoppage is transferred to said shaft.
20. A stop mechanism comprising warp supported detectors adapted to be abnormally positioned upon warp fault, a feeler adapted to move in a path that is intercepted by an abnormally positioned detector, an actuator for said feeler, a support for said actuator including a rock shaft whereon said actuator is mounted, stopping mechanism, and means rendered operative upon the occurrence of a warp fault to transfer the strain of loom stoppage to said support.
21. A stop mechanism comprising warp supported detectors adapted to be abnormally positioned upon warp fault, a feeler adapted to move in a path that is intercepted by an abnormally positioned detector, an actuator for said feeler, a rock shaft whereon the feeler is loosely mounted and whereon said actuator is fixed, stopping mechanism, and means rendered operative upon the occurrence of a warp fault to transfer the strain of loom stoppage to said shaft.
22. A stop mechanism comprising thread supported detectors adapted to be abnormally positioned upon thread fault, a feeler to engage an abnormally positioned detector, an actuator for said feeler, rotary means for operating said actuator, an abutment operatively related to the feeler to remove from the abnormally positioned detector engaged by the feeler the strain of loom stoppage, so that the strain of loom stoppage is not borne or shared by the abnormally positioned de-
- tector, and stopping mechanism made effective by the said abutment.
23. A stop mechanism comprising thread supported detectors adapted to be abnormally positioned upon thread fault, a feeler adapted to move in a path that is intercepted by an abnormally positioned detector, an actuator for said feeler, a member, one portion whereof has a normal path of movement, an abutment acting upon the occurrence of thread fault to interrupt the movement of such portion of said member, stopping mechanism, and connections whereby upon such interruption of movement the strain of loom stoppage is transferred from an abnormally positioned detector.
24. A stop mechanism comprising thread supported detectors adapted to be abnormally positioned upon thread fault, a feeler adapted to move in a path that is intercepted by an abnormally positioned detector, an actuator for said feeler, means carried by the actuator and having movement relative to the feeler and adapted to be abnormally positioned upon the occurrence of a thread fault, an abutment coöperating with said feeler and said means carried by the actuator stopping mechanism, and a movable member operatively connected with the stopping mechanism, the movement of said movable member being governed by said means when abnormally positioned.
25. A stop mechanism comprising warp supported detectors adapted to be abnormally positioned upon warp fault, a feeler adapted to move in a path that is intercepted by an abnormally positioned detector, an actuator for said feeler, a shaft about which the feeler and actuator have movement stopping mechanism, a feeler actuated member carried by said actuator and having a normal path of movement, and co-acting means consequent upon warp fault to affect the movement of said member and thereby positively to actuate the stopping mechanism.
26. A stop mechanism comprising warp supported detectors adapted to be abnormally positioned upon warp fault, a feeler adapted to move in a path that is intercepted by an abnormally positioned detector, an actuator for said feeler, stopping mechanism, an abutment carried by said feeler, a member carried by the actuator, and means whereby engagement is effected of the abutment and said member upon the occurrence of warp fault to stop the loom.
27. A stop mechanism comprising warp supported detectors adapted to be abnormally positioned upon warp fault, a feeler adapted to move in a path that is intercepted by an abnormally positioned detector, an actuator for said feeler, stopping mechanism, an abutment rigid with said feeler, a member carried by the actuator, and means whereby engagement is effected of said abut-

ment and said member upon the occurrence of warp fault to stop the loom.

28. A stop mechanism comprising thread supported detectors adapted to be abnormally positioned upon thread fault, a feeler adapted to move in a path that is intercepted by an abnormally positioned detector, an actuator for said feeler, stopping mechanism, an abutment carried by the feeler, a member operatively connected to the actuator, and means whereby engagement is effected by the abutment and member upon thread fault, thereby to stop the mechanism.

29. A stop mechanism comprising warp supported detectors adapted to be abnormally positioned upon warp fault, a feeler adapted to move in a path that is intercepted by an abnormally positioned detector, an actuator for said feeler, stopping mechanism, an abutment carried by the feeler, a member moved by the actuator, and means whereby the abutment and member engage upon warp fault, thereby to stop the loom.

30. A stop mechanism comprising thread supported detectors adapted to be abnormally positioned upon thread fault, a feeler adapted to move in a path that is intercepted by an abnormally positioned detector, an actuator for said feeler moved independently of the lay, and co-acting means having two paths of movement and confined to one of said paths of movement by contact of the feeler with an abnormally positioned detector thereby to separate the feeler and said abnormally positioned detector and to stop the machine.

31. A stop mechanism comprising thread supported detectors adapted to be abnormally positioned upon thread fault, a feeler adapted to move in a path that is intercepted by an abnormally positioned detector, an actuator for said feeler, and means rendered operative by contact of the feeler with an abnormally positioned detector upon either stroke to withdraw the feeler from said detector.

32. A stop mechanism comprising warp supported detectors adapted to be abnormally positioned upon warp fault, a feeler adapted to move in a path that is intercepted by an abnormally positioned detector, an actuator for said feeler, an abutment adapted upon engagement of the feeler with an abnormally positioned detector to be moved into impact position, and a movable member operatively connected to the actuator and adapted upon engagement with said abutment to have its path of movement affected to separate the feeler and abnormally positioned detector, and to stop the machine.

33. A stop mechanism comprising warp supported detectors adapted to be abnormally positioned upon warp fault, a feeler adapted to move in a path that is intercepted by an abnormally positioned detector,

an actuator for said feeler, an abutment adapted upon engagement of the feeler with an abnormally positioned detector to be moved into impact position, and a member carried by the actuator and adapted to engage the abutment when in impact position and thereupon to withdraw the feeler from the abnormally positioned detector.

34. A stop mechanism comprising warp supported detectors adapted to be abnormally positioned upon warp fault, a feeler adapted to move in a path that is intercepted by an abnormally positioned detector, an actuator for said feeler, said feeler having lateral projections adapted to be abnormally positioned upon engagement of the feeler with an abnormally positioned detector, stopping mechanism and a member operatively connected to said stopping mechanism and operated by said actuator and adapted to engage a lateral projection of said feeler when abnormally positioned.

35. A stop mechanism comprising warp supported detectors adapted to be abnormally positioned upon warp fault, a feeler adapted to move in a path that is intercepted by an abnormally positioned detector, an actuator for said feeler, said feeler having projections extending therefrom in the plane of movement thereof, stopping mechanism, and a member operatively connected to said stopping mechanism and operated by said actuator and adapted to engage a projection when abnormally positioned.

36. A stop mechanism comprising warp supported detectors adapted to be abnormally positioned upon warp fault, a feeler adapted to move in a path that is intercepted by an abnormally positioned detector, an actuator for said feeler, projections extending from said feeler, stopping mechanism, and a member operatively connected thereto and operated by said actuator and adapted to engage a projection when abnormally positioned.

37. A stop mechanism comprising warp supported detectors adapted to be abnormally positioned upon warp fault, a feeler adapted to move in a path that is intercepted by an abnormally positioned detector, an actuator for said feeler, a rock shaft whereon the feeler is mounted, means permitting movement of the rock shaft without movement of the feeler, a feeler actuated member, stopping mechanism, connections between said stopping mechanism and said feeler actuated member, and means whereby upon movement of the rock shaft independent of the feeler the feeler actuated member is rendered active and the loom is stopped.

38. A stop mechanism comprising warp supported detectors adapted to be abnormally positioned upon warp fault, a feeler adapted to move in a path that is intercepted by an abnormally positioned detector, an

actuator for said feeler, a rock shaft whereon the feeler and actuator are mounted, means permitting movement of the rock shaft by the actuator without movement of the feeler upon engagement of the feeler with an abnormally positioned detector, stopping mechanism, and a member operatively connected to the stopping mechanism and operated by the actuator and adapted 10 upon such independent movement of the rock shaft to operate the stopping mechanism.

39. A stop mechanism comprising warp supported detectors adapted to be abnormally 15 positioned upon warp fault, a feeler adapted to move in a path that is intercepted by an abnormally positioned detector, an actuator for said feeler, abutments carried by said feeler, stopping mechanism, a lever pivoted 20 upon the actuator and operatively connected to the stopping mechanism, and provisions whereby upon engagement of the feeler with an abnormally positioned detector said lever engages an abutment upon 25 the feeler to operate the stopping mechanism.

40. A stop mechanism comprising thread supporting detectors adapted to be abnormally positioned upon thread fault, a feeler 30 adapted to move in a path exteriorly to the detectors that is intercepted by engagement with an abnormally positioned detector, an actuator for said feeler, a secondary feeler, means to move the same, stopping mechanism, and provisions whereby when the first 35 feeler is intercepted by an abnormally positioned detector, the secondary feeler effects loom stoppage.

41. A stop mechanism comprising thread 40 supported detectors adapted to be abnormally positioned upon thread fault, an oscillatory feeler adapted to move in a path that is intercepted by engagement with an abnormally positioned detector, an actuator 45 for said feeler, a secondary feeler, means to move the same in a determined path to be intercepted when the first feeler encounters an abnormally positioned detector, stopping mechanism and connections therefrom to 50 said secondary feeler, whereby the loom is stopped when the secondary feeler is intercepted.

42. A stop mechanism comprising thread supported detectors adapted to be abnor- 55 mally positioned upon thread fault, a feeler adapted to move in a path that is inter- cepted by an abnormally positioned detector and operative upon either stroke, an actuator for said feeler, and means operative 60 upon either stroke of said feeler in the event of the abnormal positioning of a detector to separate the feeler and said detector.

43. A stop mechanism comprising thread 65 supported detectors adapted to be abnor-

mally positioned upon thread fault, a feeler adapted to move in a path that is intercept- ed by an abnormally positioned detector, an actuator for said feeler, an abutment so oper- atively connected to the feeler as to be 70 positioned by an indicating drop for loom stoppage, and a bunter distinct from the lay and adapted to engage said abutment, thereby to stop the loom while removing from the abnormally positioned detector the 75 strain of loom stoppage.

44. A stop mechanism comprising thread supported detectors adapted to be abnor- 80 mally positioned upon thread fault, a feeler adapted to move in a path that is intercept- ed by an abnormally positioned detector, an actuator for said feeler, a bunter operated by a going part of the loom distinct from the lay, and an abutment having a yielding 85 connection with said actuator and adapted to be engaged by said bunter to stop the loom.

45. A stop mechanism comprising warp supported detectors adapted to be abnor- 90 mally positioned upon warp fault, a feeler adapted to move in a path that is intercept- ed by an abnormally positioned detector, an actuator for said feeler, stopping mecha- nism, an abutment having a support com- 95 mon with that of said feeler, and a bunter 100 to engage said abutment and having connections to impart thereto a normal path of movement, said bunter and said abut- ment being so relatively mounted as to be brought into engagement in the event of warp fault, said engagement of the bunter and abutment effecting a change in the path 105 of movement of said bunter, thereby to ac- tuate said stopping mechanism.

46. A stop mechanism comprising warp supported detectors adapted to be abnor- 110 mally positioned upon warp fault, a feeler adapted to move in a path that is intercept- ed by an abnormally positioned detector, an actuator for said feeler, a rock shaft 115 whereon the feeler is mounted, means per- mitting movement of the rock shaft without movement of the feeler, a feeler actuated member, stopping mechanism, and connec- tions between said stopping mechanism and said feeler actuated member.

47. A stop mechanism comprising warp supported detectors adapted to be abnor- 120 mally positioned upon warp fault, a feeler adapted to move in a path that is intercept- ed by an abnormally positioned detector, an actuator for said feeler, a rock shaft whereon the feeler and actuator are mounted, means permitting movement of the rock shaft by the actuator without movement of the feeler upon engagement of the feeler with an abnormally positioned detector, and stopping mechanism operated upon inter- 125 cepted movement of the feeler.

48. A stop mechanism comprising thread 130

- supported detectors adapted to be abnormally positioned upon thread fault, a feeler adapted to move in a path that is intercepted by an abnormally positioned detector, 5 means distinct from the lay for so moving said feeler, a bunter operated independently of the lay and operatively related to the feeler to remove from the abnormally positioned detector the strain of loom stoppage, 10 whereby the strain of loom stoppage is not borne nor shared by the abnormally positioned detector, and stopping mechanism made effective by the bunter and independently of the lay.
- 15 49. A loom stop mechanism comprising warp supported detectors adapted to be abnormally positioned upon warp fault a feeler adapted to move in a path that is intercepted by an abnormally positioned detector, a cam upon the weft cam shaft for so moving the feeler, a bunter operated independently of the lay and operatively related to the feeler to remove from the abnormally positioned detector intercepting 20 the feeler the strain of loom stoppage, whereby the strain of loom stoppage is not borne nor shared by the abnormally positioned detector, and stopping mechanism made effective by the bunter.
- 25 50. A loom stop mechanism, comprising thread supported detectors adapted to be abnormally positioned upon thread fault, a feeler to engage an abnormally positioned detector, an actuator for said feeler, means 30 distinct from the lay and operatively related to the feeler to remove from the abnormally positioned detector the strain of loom stoppage and stopping mechanism made effective by said means.
- 35 51. A loom stop mechanism comprising thread supported detectors adapted to be abnormally positioned upon thread fault, a feeler to engage an abnormally positioned detector, an actuator for said feeler, a bunter 40 supported by said actuator to remove from the abnormally positioned detector the strain of loom stoppage, and stopping mechanism made effective by said bunter.
- 45 52. A loom stop mechanism comprising thread supported detectors adapted to be abnormally positioned upon thread fault, a feeler to engage an abnormally positioned detector, an actuator for said feeler, means including an abutment to remove from the 55 abnormally positioned detector the strain of loom stoppage, said actuator having a part whereon said abutment is pivoted, and stopping means made effective by said means.
- 60 53. A stop mechanism comprising thread supported detectors adapted to be abnormally positioned upon thread fault, a feeler having a movable support adapted to move in a path that is intercepted by an abnormally positioned detector, an actuator for 65 said feeler, means distinct from the lay for operating said actuator, an abutment independent of the lay and rigid with the feeler, a moving member and provisions whereby said abutment is held in the path of the moving member upon the occurrence of a 70 thread fault.
54. A stop mechanism comprising thread supported detectors adapted to be abnormally positioned upon thread fault, a feeler adapted to move in a path that is intercepted by an abnormally positioned detector, an actuator for said feeler, a plurality of abutments normally in inoperative position, means to move the said abutments into operative position and connections including 75 means movable with the actuator whereby movement of either of said abutments into operative position actuates the stop mechanism.
55. A stop mechanism comprising warp supported detectors adapted to be abnormally positioned upon warp fault, a feeler adapted to move in a path that is intercepted by an abnormally positioned detector, and positioned and arranged to contact with 80 the outer surface of an abnormally positioned detector, an actuator for said feeler, stopping mechanism, an abutment rigid with the feeler, independent of the lay and normally inoperative, and means operative 85 upon either stroke of the feeler and including a bunter for said abutment whereby the loom is stopped upon the occurrence of a warp fault.
56. A stop mechanism comprising thread supported detectors adapted to be abnormally positioned upon thread fault, a feeler adapted to move in a path that is intercepted by an abnormally positioned detector, an actuator for said feeler, coöperating means 90 having two curved paths of pivotal movement about two centers and confined to one of said paths of movement by contact of the feeler with an abnormally positioned detector, thereby to separate the feeler and 95 said abnormally positioned detector and to stop the machine.
57. A stop mechanism comprising thread supporting detectors adapted to be abnormally positioned upon thread fault, a feeler adapted to move in a path that is intercepted by an abnormally positioned detector, an actuator for said feeler, a feeler actuated member normally movable in a determined path and constructed and arranged upon 100 engagement of the feeler with an abnormally positioned detector to engage said feeler and to have such path of movement 105 thereby affected, stopping mechanism, and a stoppage actuating connection between the feeler actuated member and the stopping mechanism rendered operative when such 110 path of movement is affected.
58. A stop mechanism comprising thread supported detectors adapted to be abnor- 115
- 65 120
- 125
- 130

5 mally positioned upon thread fault, a feeler adapted to move in a path that is intercepted by an abnormally positioned detector, an actuator for said feeler, a plurality of abutments in proximity to said feeler and normally in inoperative position, said abutment being constructed and arranged whereby upon the occurrence of a thread fault one of said abutments is operatively positioned, 10 and stopping mechanism rendered operative thereby and including means adapted to contact with the operatively positioned abutment.

59. A stop mechanism comprising warp supported detectors adapted to be abnormally positioned upon warp fault, a feeler adapted to move in a path that is intercepted by an abnormally positioned detector, an actuator for said feeler, stopping mechanism, a plurality of abutments independent of the lay and carried by the feeler and normally inoperative, and means operative upon either stroke of the feeler and including a bunter, and a feeler actuated member 20 normally movable in a determined path and adapted upon engagement of the feeler with an abnormally positioned detector to have such path of movement thereby affected, whereby the loom is stopped upon the occurrence of a warp fault.

60. A stop mechanism comprising thread supported detectors adapted to be abnormally positioned upon thread fault, a feeler adapted to move in a path that is intercepted by an abnormally positioned detector, and having an abutment portion, an actuator for said feeler, means carried by the actuator and extending into proximity to the feeler and adapted to be abnormally positioned upon the occurrence of a thread fault and to engage the abutment portion of said feeler, stopping mechanism, and a movable member operatively connected with the stopping mechanism, the movement of said 45 movable member being governed by said means when abnormally positioned.

61. A stop mechanism comprising thread supported detectors adapted to be abnormally positioned upon thread fault, a feeler adapted to move in a path that is intercepted by an abnormally positioned detector, an actuator for said feeler, a plurality of abutments carried by the feeler and normally in inoperative position, said abutments being constructed and arranged to move into operative position and connections whereby movement of either of said abutments into operative position actuates the stop mechanism and including means 60 adapted to contact with the operatively positioned abutment.

62. A stop mechanism comprising thread supported detectors adapted to be abnormally positioned on thread fault, a feeler to engage an abnormally positioned detector,

an actuator for said feeler, means having a continuous movement in one direction for operating said actuator, an abutment operatively related to the feeler to remove from the abnormally positioned detector engaged by the feeler the strain of loom stoppage, so that the strain of loom stoppage is not borne or shared by the abnormally positioned detector, and stopping mechanism made effective by and operatively associated with said abutment. 70 75

63. A stop mechanism comprising thread supported detectors adapted to be abnormally positioned upon thread fault, a feeler adapted to move in a path that is intercepted by an abnormally positioned detector, an actuator for said feeler, means driven at a less speed than the main drive shaft of the machine for operating said actuator, stopping mechanism, and an abutment operatively related to the feeler to remove the strain of loom stoppage from an abnormally positioned detector intercepting the feeler and operatively connected to said stopping mechanism, so that the strain of loom stoppage is not borne or shared by the abnormally positioned detector. 80 85 90

64. A stop mechanism comprising warp supported detectors adapted to be abnormally positioned upon warp fault and a feeler adapted to move in a path that is intercepted by an abnormally positioned detector, an actuator for said feeler, means driven at a less speed than the main drive shaft of the machine for operating said actuator, stopping mechanism, and an abutment to remove, prior to loom stoppage, the strain of the feeler from an abnormally positioned detector intercepting the feeler, whereby the strain of loom stoppage is not 105 borne nor shared by the abnormally positioned detector. 95 100

65. A stop mechanism comprising thread supported detectors adapted to be abnormally positioned upon thread fault, a feeler adapted to move in a path that is intercepted by an abnormally positioned detector, an actuator lever for said feeler, a feeler actuated member carried by the actuator lever and having movement relative to the feeler, said feeler actuated member being normally movable in a determined path and adapted to have its path of movement modified upon engagement of the feeler with an abnormally positioned detector, stopping mechanism and a stoppage actuating connection between the feeler actuated member and the stopping mechanism rendered operative when such path of movement is affected. 110 115 120 125

66. A stop mechanism comprising thread supported detectors adapted to be abnormally positioned upon thread fault, a feeler adapted to move in a path that is intercepted by an abnormally positioned detector, an ac- 130

tuator for said feeler, a plurality of abutments normally in inoperative position, means to move the said abutments into operative position, and connections including 5 means movable with and also relatively to the actuator, whereby movement of either of said abutments into operative position actuates the stop mechanism.

In testimony whereof, I have signed my name to this specification, in the presence of 10 two subscribing witnesses.

CHARLES D. LANNING.
